UNITED STATES PATENT OFFICE.

OTTO WALTER, JR., OF DE KALB, ILLINOIS.

ROOFING-TILE MACHINE.

1,252,208,

Specification of Letters Patent.

Patented Jan. 1, 1918.

Application filed April 6, 1917. Serial No. 160,200.

To all whom it may concern:

Be it known that I, OTTO WALTER, Jr., residing at De Kalb, in the county of De Kalb, State of Illinois, United States of America, have invented certain new and useful Improvements in Roofing-Tile Machines, of which the following is the specification.

My invention relates to improvements in roofing tile machines and the object of the invention is to increase the capacity of a machine of this type whereby a plurality of molds may be employed and mechanism for simultaneously lifting the pallets in the molds, a subsidiary object being to provide a simple means for locking the pallet lifting mechanism in the raised position, a further object being to provide simple means for detachably securing the needle within its supporting arm and it consists essentially of the following arrangement and construction of parts as hereinafter more particularly explained.

Figure 1, is a general perspective view of my device.

Fig. 2, is a cross sectional view taken through the upper portion of my device.

Fig. 3, is a sectional detail showing the means for locking the lifting mechanism in the raised position.

In the drawings like letters of reference indicate corresponding parts in the various figures.

1 indicates the main frame, comprising the upper longitudinal members 2 and 3 connected by cross members 4 and 5 at their ends. The members 2 and 3 and 4 and 5 form the top frame, which is supported upon standard legs 6, 7, 8 and 9, the standard legs 6 and 7 being connected together by upper and lower cross bars 10 and 11, and the standard members 8 and 9, by corresponding cross bars 12 and 13.

14 and 15 indicate the molds which are formed integral with cross bars 16 and 17, which are supported at their ends upon the longitudinal bars 2 and 3. 18 indicates a bar secured at its ends to the cross bars 10 and 12, such bar extending centrally across the machine. 19 indicates a semi-circular bar portion which is secured at its ends to the cross bars 11 and 13 and extends upwardly beneath the center portion of the bar 18 forming a support therefor. 18^x indicates an orifice formed in the cross bar 18 and 19^x indicates an orifice formed in the bar 19.

It will be noted particularly from Fig. 1 that the molds 14 and 15 are open bottom molds.

20 and 21 indicate crossed bars located between the mold 15 and 22 and 23 indicate crossed bars located beneath the mold 14. 24 and 25 indicate vertical rods, the upper ends of which extend respectively through the intersection of the cross bars 20 and 21 and 22 and 23 and are suitably secured therein. 26 indicates a bar extending between the rods 24 and 25, and through which the rods extend. 27 indicates a downwardly curved bridging piece forming a truss support, extending beneath the bar 26, the ends of such bridging piece 27 being provided with vertically disposed sleeve-like portions 29 and 30 through which the rods 24 and 25 extend, such rods being held in position by nuts 31 bearing against the lower end of the portions 29 and 30, and nuts 32 bearing against the upper face of the bar 26. The rods 24 and 25 depend downwardly freely through orifices 33 and 34 formed respectively in the bars 18 and 19.

35 indicates the main operating rod, which extends freely upwardly through orifices 18^x and 19^x and is provided with a threaded upper end, which extends through an orifice 36 formed in the bridging bar 27 and an orifice 37 formed in the bar 26. 38 and 39 indicate nuts screwed on to the rod 35 above and below the bar 26 and 40 and 41 indicate nuts screwed upon the rod 35 above and below the bridging bar 27. 42, 43, 44 and 45 indicate pins extending upwardly from the cross bars 20 and 21 through orifices 46 formed in the cross bars 16 and 17 within the mold 15 and 47, 48, 49 and 50 indicate pins extending upwardly from the ends of the cross bars 22 and 23 through orifices 51 formed in the cross bars 16 and 17 within the mold 14. 52 indicates the pallets located within the molds 14 and 15. The pallet 52 is provided with a central orifice 53. 54 indicates a rocking rod journaled at its ends in the bars 2 and 3 of the main frame and provided at one end with a crank handle 55. 56 indicates arms formed in two portions 57 and 58 secured together by a bolt 59. The inner opposing faces of the portions 57 and 58 are provided with grooves 60 and 61. 62 indicates a wire needle extending into such grooves and is clamped therein by the bolt 59 when the parts 57 and 58 are drawn together. The arm 56 is

secured to the rocking rod and when the crank 56 is depressed the needle 62 is carried up through the orifice 53 and through a portion of the material forming the tile 5 to form a perforation therethrough as is now commonly done in tiles of this type. 63 indicates a foot lever fulcrumed at 64 and connected at its inner end by a link 65 to the lower end of the operating rod 35. 10 66 indicates a rocking rod supported in bearings 67 and 68 carried by the bar 18. The upper end of the rod 66 is provided with a weighted crank handle 69 extending into a limiting slot 70. The opposite or 15 inner end of the rod 66 is provided with an out-turned portion 71 extending at an opposite angle to the crank handle 69.

Having described the principal parts involved in my invention I will briefly describe the operation of the same.

The pallets 52 are set in the molds 14 and 15 so as to rest upon the ends of the pins 42, 43, 44 and 45 in the mold 15 and on the pins 47, 48, 49 and 50 in the mold 14. The material is then fed into the molds and when sufficiently set the foot lever 63 is depressed so as to raise the operating rod 35 vertically carrying the cross bars 20 and 21 and 22 and 23 and the pins 42, 43, 44, 45, 46, 47, 48, 25 49 and 50 carried thereby upwardly thereby lifting each pallet 52 of the molds 14 and 15 simultaneously to the discharge position, the pallets being automatically locked in such position by the out-turned portion 71 being 30 carried to a vertical position beneath the nut 41 by the dropping of the weighted crank handle 69 to its lower position. The pallets and tiles may then be removed and when removed the crank handle 69 can be again 35 raised so as to carry the out-turned end 71 from beneath the nut 41 and thereby allow the cross bars 20, 21, and 22 and 23 and pins carried thereby to drop to their normal 40 position ready to receive a new pallet. 45 By connecting the cross bars 20 and 21 and 22 and 23 by cross bar 26 and bridging bar 27 and rods 24 and 25, which rods pass through orifices formed in the cross bar 18 and truss bar 19 a very rigid construction 50 is provided, which will absolutely insure of

the even upward simultaneous movement of the pallets when such pallets are raised by the operation of the foot lever 63.

By providing the locking mechanism as above described it will be seen that when the pallets are raised they are held in a definite position so as to enable the operator to remove the pallets and tiles from both molds without any danger of the pallets dropping again into the mold during the removal of the first tile and thereby spoiling the remaining tiles.

What I claim as my invention is:

1. In a roofing tile machine, the combination with a plurality of open bottomed molds, of raisable means for supporting a pallet within each open bottomed mold, means connecting such raisable means together to operate simultaneously, and a finger swingably supported at its lower end and adapted to automatically assume a vertical position beneath the connecting means to support the raisable means in the raised position.

2. In a roofing tile machine, the combination with a plurality of open bottom molds, of raisable means for supporting a pallet within each open bottom mold, means connecting such raisable means together to operate simultaneously, a rocking rod journaled in suitable bearings, a weighted crank handle at one end, and a portion at the opposite end out-turned at an opposite angle to the crank arm and adapted to be carried by the crank arm to a vertical position beneath the connecting member of the raisable means when such raisable means are carried to the raised position.

3. In a roofing tile machine, a perforating device comprising a suitably journaled rocking rod, a crank handle at one end and arms comprising two portions having opposing grooves adapted to receive an arc-shaped perforating needle, and a bolt connecting such portions together to clamp the needles within the grooves.

OTTO WALTER, JR.
